FRED S. MAKER, OF SEEKONK, MASSACHUSETTS, AND RALPH K. MAKER, OF PROVIDENCE, RHODE ISLAND, ASSIGNORS TO IDEAL JEWELRY MANUFACTURING COMPANY, OF PROVIDENCE, RHODE ISLAND, A CORPORATION OF RHODE ISLAND.

BAR PIN AND METHOD OF MAKING THE SAME.

Application filed October 15, 1921. Serial No. 508,039.

To all whom it may concern:

Be it known that we, FRED S. MAKER and RALPH K. MAKER, citizens of the United States, residing at Seekonk and Providence, 5 in the counties of Bristol and Providence and States of Massachusetts and Rhode Island, respectively, have invented certain new and useful Improvements in Bar Pins and Methods of Making the Same, of which 10 the following is a specification.

This invention relates to an improved bar pin and method of making the same, and more particularly a structure of this character which may be readily and easily 15 formed from plate material and the parts quickly assembled to form a pin of pleasing appearance wherein ornamental stones are held in position and positively held against becoming lost.

20 One object of the invention is to provide an improved method of forming devices of this character wherein the several parts can be readily and quickly formed and easily assembled to provide a device of this character 25 having an attractive appearance.

Another object of the invention is to provide an improved device of this character wherein ornamental stones are held in position and given the appearance of being set 30 in the surface of the material and at the same time so held in place as to prevent their becoming dislodged from the setting.

Another object of the invention is to provide a simple and easily constructed device 35 of this character the parts of which may be readily formed and easily assembled to form a substantial structure of attractive appearance.

Other objects and advantages of the invention relate to certain methods of construction and detailed arrangement of the parts as will be more fully set forth in the description to follow.

Referring to the drawings:

45 Fig. 1 is a top plan view of a piece of channel shaped stock.

Fig. 2 is a top plan view of the stock showing the same after portions of the sides have been removed indicating the points where

the stock is to be cut to form bars of the 50 desired length.

Fig. 3 is a perspective view of one of the portions into which the stock is cut after the gem seats have been formed therein.

Fig. 4 is a perspective view of the channel shaped member after openings have been formed in the side and end portions and lugs cut out from the sides.

Fig. 5 is a perspective view of the channeled member showing ornamental stones 60 positioned in the openings in the base thereof and a holding plate positioned over the stones, one side of the channel shaped member being broken away to better illustrate the position of the parts.

65 Fig. 6 is a perspective view illustrating the manner of forming the back plate.

Fig. 7 is a perspective view of the structure showing the back plate being inserted in the channeled member to form the completed structure.

70 Fig. 8 is a top plan view of the completed structure, and,

Fig. 9 is a sectional view taken along the line 9—9 of Fig. 8.

75 In the manufacture of bar pins and similar devices by methods heretofore employed considerable time and labor has been required to form the bar and provide openings therein for the reception of ornamental stones, 80 and the operation of setting each stone in the openings and bending portions of the metal thereover to hold the stones in place has required a considerable amount of skilled labor. Moreover in structures thus made the 85 metal prongs for holding the stones in place are liable to become bent and thus some of the stones may eventually become loosened from their setting and frequently be lost.

90 In order to overcome these difficulties and provide a construction wherein the stones will be positively held against becoming lost as well as to devise a structure which can be readily and easily constructed without requiring the use of highly skilled labor we 95 have had recourse to the following method of construction and arrangement of parts.

In the method employed by us, we are

accustomed to use stock which has previously been rolled out into channel shaped form as shown in Fig. 1 although the stock may be bent into the desired form by the 5 use of presses or formed in any other desired manner. In the carrying out of our method of operation the stock as indicated by the reference character 1, which comprises a base portion 2 and side portions 3 10 and 4, is first operated upon by cutting out portions of the sides 3 and 4 as indicated at 5 and 6 to form ends for the separate channel shaped members and the stock is then cut into sections as indicated by the line 15 4-4 in Fig. 2 of the drawings to obtain a channel shaped member as shown in Fig. 3. The member thus formed is then placed 20 in a press or otherwise suitably operated upon to cut out openings 7 in the base thereof of suitable size to serve as seats for the stones which are to be used and openings 8 are formed in the sides 3 and 4 as well as similar openings 9 in the ends 10. The order in which the openings 7, 8 and 9 are 25 formed is not material to the formation of the structure and may be varied as desired. Preferably simultaneously with the formation of the openings 8 in the sides 3 and 4, cuts 11 are formed in the sides 3 and 4 to 30 cut the stock upon three sides of rectangles of substantially equal area to the rectangular openings 8 and the rectangular lugs 12 thus formed in the sides are driven inwardly slightly during the cutting operation 35 as indicated in Fig. 5. It will be noted that in the present instance three of these lugs are formed in each of the sides 3 and 4, although a greater or less number may be formed as appears desirable, and the rectangular lugs thus formed are located in 40 line with and are of substantially the same size as the openings 8. After the channel shaped member has been formed as above described, one of the ends 10 is bent up 45 into contact with the adjacent ends of the sides 3 and 4 as shown in Fig. 5 and ornamental stones 14 are seated in the openings 7 formed in the base of the channelled member, the stones being properly positioned 50 to expose the faces thereof through the openings 7 in the base of the member. A holding plate 15 provided with a plurality of suitably spaced openings 16 formed therein is then placed back of the stones 14 and 55 so positioned that the rear portions of the ornamental stones will register with and project into the openings 16 formed in the holding plate.

The lugs 12 being, as previously stated, 60 only slightly bent inwardly from the sides 3 and 4, the plate 15 may be laid directly upon the stones, there being sufficient clearance between the side edges of the plate 15 and the sides 3 and 4 to permit the 65 insertion of the plate. The structure is now

preferably placed in a suitable press or otherwise operated upon to press the lugs 12 farther inwardly into the position indicated in Figs. 7 and 9, thus engaging the plate 15 to prevent it from accidental displacement while leaving sufficient space between the plate 15 and the lugs 12 to permit the insertion of a back plate as will be hereinafter described.

The back plate 20 is V-shaped in cross-section and is preferably formed from a plane strip 21 by rolling the same as indicated in Fig. 6 of the drawings, although any other suitable or desired method of forming the back plate may be employed. The 75 V-shaped stock is cut into suitable lengths to form the back plates 20 and a pin base 22 and clasp 23 are secured to each, as by soldering, to form the completed back plate. A pin 24 is suitably mounted in the base 22 80 and is adapted to engage the clasp 23 for securing the bar pin to fabric as is well known in the art. The completed back plate is inserted into the channel shaped member through the open end portion thereof, as 85 shown in Fig. 7 of the drawings, and forced inwardly beneath the lugs 12 thus pressing the back plate 15 firmly into engagement with the stones 14 and securely holding all 90 of the parts against separation. There remains only to bend up the end 10 through which the back plate has been inserted to form the completed structure as shown in 95 Figs. 8 and 9 wherein the stones are seated in the openings formed in the base portion 100 of the channelled member and engaged and held in position by the holding plate while the back plate interposed between the lugs 12 and the holding plate binds the several 105 parts securely in place.

It will be noted that after the lugs 12 are bent down as shown in Figs. 7 and 9 of the drawings the openings remaining constitute with the openings 8 previously formed a series of ornamental openings extending throughout the sides of the channel shaped member, and these appreciably add to the ornamental appearance of the structure. The openings 9 formed in the end portions 10 of the channelled member 110 may, if desired, be dispensed with to have the ends display unbroken plane surfaces to view. In the formation of the V-shaped back plate and the bending of the lugs 12, the lugs 12 may be bent down to form a 115 more acute angle with the holding plate, as shown in Fig. 9 of the drawings, and the form of the back plate correspondingly modified to bring the apex of the back plate 120 into closer relationship with the base of the stones.

We preferably provide an ornamental surface for the exposed face of the channel shaped member, as illustrated in Fig. 8 of the drawings, comprising an ornamental 125

border 25, a bevel portion 26 and ornamental depressions 27 to simulate the appearance of a surface set pin.

While we have described our improved structure and our preferred method of making the same with considerable particularity in order to make clear to those skilled in the art the series of steps which may be employed, we are aware that various equivalent steps in the mode of operation may be substituted for those herein described, and that certain modifications in the structure may be made without departing from the spirit and scope of our invention, therefore we do not desire or intend to be limited to the precise steps or sequence of steps described herein nor to the precise details of construction shown and described except as the same may be properly included within the scope of the appended claims when broadly construed in the light of our invention.

Having described our invention, what we claim is:

1. The method of making a bar pin of the character described which comprises, the cutting of a plurality of openings in the base portion of a channel shaped metal plate, striking out inwardly extending lugs from the sides of said channeled plate, the placing of ornamental stones in the openings cut in said channeled plate, the positioning of a holding plate in contact with the said stones to hold them in proper position relative to said channeled plate, the bending of the lugs into close relation to said holding plate, and the insertion of a back plate between said lugs and said holding plate.

2. The method of making a bar-pin of the character described which comprises, cutting a plurality of openings in the base portion of a channel shaped metal plate, striking out lugs upon the sides of said channel shaped plate, placing ornamental stones in position within said channeled plate so that a portion of each stone will project through the openings in said plate, placing a holding plate in contact with said stones, and sliding a back plate into said channeled plate beneath said lugs to bear against the holding plate and retain the several parts in against separation.

3. The method of forming a bar-pin of the character described which comprises, cutting a plurality of openings in the base portion of a channel shaped metal plate, forming inwardly extending lugs upon the side portions of said plate, placing ornamental stones in position in said openings, and inserting holding plates between said stones and said lugs to hold the stones in proper position and bind the several parts against separation.

4. The method of forming a bar pin of the character described which comprises, form-

ing a channel shaped base plate provided with a plurality of openings, cutting ornamental openings in the sides thereof, striking out lugs from the sides thereof, inserting ornamental stones in said first named openings, and inserting holding plates between said stones and said lugs to hold the stones in position and bind the several parts against separation.

5. In a bar pin of the character described, a channel shaped plate provided with a plurality of openings in the base thereof and a plurality of lugs formed upon the side portions of said plate, ornamental stones seated in the said openings formed in the base portion of said plate, a holding plate contacting with said stones to hold the same in position, and a base plate slidably insertible from one end of said channel shaped plate and positioned between said lugs and said holding plate.

6. In a bar pin of the character described, a channel shaped plate, provided with lugs struck inwardly from the sides thereof and a plurality of openings formed in its base portion, stones seated in said openings and removable plates positioned between said lugs and said stones to securely retain the various parts in position.

7. In a bar pin of the character described, a channel shaped plate provided with lugs struck inwardly from the sides thereof and a plurality of openings formed in its base portion, stones seated in said openings, and means interposed between said lugs and said stones for securely retaining the stones in position in the several openings.

8. In a bar pin of the character described, a channel shaped plate provided with a plurality of openings in the main body portion thereof to serve as seats for ornamental stones, stones seated in said openings, lugs struck inwardly from the sides of said plate, a holding plate provided with openings registering with said stones, and means removably positioned between said lugs and said holding plate to hold the several parts against separation.

9. In a bar pin of the character described, a channel shaped plate provided with a plurality of openings formed in the base portion thereof to form seats for ornamental stones, a plurality of ornamental openings formed in the sides thereof, and lugs projecting inwardly from the sides thereof; stones seated in said first named openings; and means interposed between said lugs and said stones to hold the stones properly positioned in the openings and retain the several parts against separation.

10. In a bar pin of the character described, a channel shaped plate having a plurality of openings formed in the base thereof to provide seats for ornamental stones, ornamental stones seated in said openings, and remov-

able means positioned in the channel portion of the plate for holding the stones seated in said openings.

11. In a bar pin of the character described, a channel shaped plate having a plurality of openings formed in the base thereof to provide seats for ornamental stones, ornamental stones seated in said openings, and means po-

sitioned in the channel portion of the plate for holding the stones seated in said openings.

In testimony whereof we have affixed our signatures.

FRED S. MAKER.
RALPH K. MAKER.
